R. T. ROMINE

PAINT STICK FOR AUTOMOBILES

Filed Sept. 3, 1926

By

Robert T. Romine Inventor

MacLeod, Calver, Copeland & Dick
E 2 Attorneys.

UNITED STATES PATENT OFFICE.

ROBERT T. ROMINE, OF MOUNT CLEMENS, MICHIGAN.

PAINT STICK FOR AUTOMOBILES.

Application filed September 3, 1926. Serial No. 133,372.

This invention relates to paint sticks adapted to be attached to automobile bodies for the purpose of facilitating the transportation of the bodies in the automobile plant 5 to and from the enamelling ovens, or for carrying the bodies along an assembly line where the frame work of the body may be assembled or the body trimmed during its travel, or for enabling the bodies to be 10 wheeled or rolled in the plant to the point where they are assembled with the chassis of the car.

An object of the invention is to provide a paint stick having casters or antifriction 15 rollers and so constructed that it may be readily attached to or detached from the car body while at the same time enabling the body to be transported, stored or otherwise conveyed so as to occupy a minimum of 20 overhead space and to be transported close to the floor thereby facilitating the assembly, trimming, inspection, enamelling or painting of the body, as well as the compact loading of the bodies in trailers or 25 freight cars.

Other objects of this invention will appear in the following description and appended 30 claims, reference being had to the accompanying drawings forming a part of this specification wherein like reference characters designate corresponding parts in the several views.

Fig. 1 is a plan view showing a paint stick 35 embodying my invention.

Fig. 2 is a side elevation of the paint stick shown in Fig. 1.

Fig. 3 is a section taken on lines 3—3, 40 Fig. 1.

Fig. 4 is a section taken on lines 4—4, 45 Fig. 1.

Fig. 5 is a perspective view showing one 50 of the clamping members.

Fig. 6 is a perspective view illustrating 55 the clamping members and the manner in which the paint stick is secured to the sill of the car body.

Before explaining in detail the present 60 invention, and method or mode of operation embodied therein, it is to be understood that the invention is not limited in its application to the details of construction and arrangement of parts illustrated in the assem-

panying drawings, since the invention is capable of other embodiments and of being practiced or carried out in various ways. 55 Also it is to be understood that the phraseology or terminology employed herein is for the purpose of description and not of limitation, and it is not intended to limit the invention beyond the terms of the several 60 claims hereto appended or the requirements of the prior art.

The present paint stick is of such improved construction as to occupy a minimum of space beneath the body, while permitting the body to roll freely on the floor or other supporting surfaces. In its preferred form the paint stick in general comprises an inverted channel bar adapted to extend beneath the body and provided with swivelled 70 casters and also devices for detachably connecting the paint stick bar to the bottom sills of the car body. This improved construction enables the frame sections of the car body to be assembled on the paint sticks while the latter are supported on an endless conveyor buck. It also enables the body to 75 be rolled into and out of the enamelling ovens while occupying but slightly more space than the body itself.

An important advantage therefore of the present invention resides in fact that the bodies may be stored or moved from place to place on the paint sticks which occupy approximately one-thirtieth of the space required for the trucks heretofore employed in moving automobile bodies during the process of manufacture. Thus the body when mounted on the paint sticks or caster bars occupies but slightly more total space 80 than the cubical space taken up by the body, whereas heretofore the dimensions, and particularly the height, of the trucks upon which the bodies were carried were such as to cause the trucks to take up considerable 85 useful space in the plant. My invention not only releases most of this space but enables the bodies to be transported, moved, or stored in double deck relation, such as shown in my co-pending applications, Serial No. 141,133, filed October 12, 1926; and Serial No. 133,375, filed September 3, 1926.

A further advantage resides in the fact 90 that the bodies may be conveyed along

assembly line within a few inches of the car floor so as to be at the proper height to permit the workmen to work on the exterior and interior of the body. Furthermore, the bodies may be loaded on the paint sticks in freight cars or in trailers in double decked relation, enabling them to be rolled into and out of the conveyances into elevators, etc., with dispatch and with a minimum of manual labor.

The paint stick comprises a channel bar 9 which in the present instance is shaped to support the bottom sills of the car body and to facilitate the assembly of the frame work of the body on the paint sticks. In its present form therefore the channel bar 9 has a central portion thereof depressed at A to bring the guides C and D hereinafter described, in relatively close proximity to the floor. The ends B of the channel bar are depressed so as not only to provide clearance but to enable casters or antifriction rollers of small diameter to be used.

The channel bar 9 is mounted in inverted position, the top flange or web providing flat supporting surfaces for the body sills. The opposite depending side flanges 9^a of the channel are strengthened and braced by means of a channel strip or bar 10 having short depending side flanges 10^a abutting against the inner lower faces of the flanges 9^a and secured thereto as by welding. The channel strip 10 terminates at 10^b sufficiently short of each end of the bar 9 to permit the upper part of the caster to be housed within each end of the channel bar 9. Each caster structure comprises a housing 11 within which is a ball-bearing race for the caster wheel or roller 12 which is swivelled to the housing, and the latter is bolted at 13 to the top flange of the channel bar 9.

The paint stick is provided adjacent each end, and between the casters, with means for releasably connecting it to the side sills of the body. In the present instance the bar 9 is offset to provide a shoulder E near each end and mounted on the bar at this point is a plate 14 bent at 14^b and 14^c to provide a transverse rib or abutment 14^a, and from this abutment the plate has a projecting flat portion 14^d for supporting a portion of the sill. The plate 14 is riveted at 15 to the upper flange of the bar 9, and adjacent the inner side of the abutment 14^a a pair of projections 16 are struck up from the metal of the plate.

The abutment 14^a forms one of the cooperating parts of a clamping device, the other part comprising a movable clamping member 17. This latter member is provided at opposite sides with depending flange portions 17^a embracing opposite sides of the channel bar 9, and the rear edge of the clamp 17 is bent downwardly to form a short flange 17^b, engaging the top of the bar 9 and en-

abling the clamp 7 to be rocked. The opposite edge of the clamp 17 is provided with a projecting lip 18 which is provided with two slots 19 to receive the projections or lugs 16, and the lip 18 is turned up to provide bottom curved surfaces 19^a enabling these portions to slide over the flange of the body sill.

The clamp member 17 is connected to the bar 9 by means of a fixed bolt 20 having a depending threaded shank 20^a projecting through an elongated slot 8 in the bar, and the clamp member may be rigidly secured to the bar by means of a nut 21.

Each body sill in the present instance comprises a metal bar 23 bent in the form of a channel, and is adapted to fit over the abutment 14^a, as shown in Fig. 2. A flange 25 of the sill is adapted to rest upon the flat portion 14^d of the clamp plate 14, and another flange 24 of the sill is supported at the opposite side of the abutment 14^a. It will be seen that the sill 23 has a shoulder 24^a which engages the shoulder 14^b, and the sill is notched to receive the lugs or projections 16.

By means of the slot 8 the clamp member 17 may be shifted toward and from the abutment 14^a, and a rocking movement is permitted by means of the lip or flange 17^b of the clamp member. When the sills 23 of the automobile body are placed in position on the paint stick as shown in Fig. 2 the clamp member 17 is then shifted toward the abutment 14^a so that the lip portions 18 will overlie the flange 24 of the sill and with the lugs 16 extending into the slot 19 of the clamp. Thereafter the nut 21 is turned so as to tighten the clamp member and thereby lock the sill in position on the paint stick.

The paint stick is also provided with guides which are adapted to cooperate with a stationary guide on the floor during the travel of the body on the paint stick, thereby enabling the body to be moved on the floor in a predetermined path as by means of a suitable chain conveyor. The guides C and D are formed in the present instance by means of plates 27 and 29 riveted at 30 to the bottom of the channel strip 10, as shown in Fig. 3. These plates are bent downwardly at 27^a and 29^a and these depending portions are arc shaped or convex. An intermediate plate 28 is also riveted to the channel strip 10 and the opposite ends thereof are bent the reverse of the portions 27^a and 29^a to provide oppositely curved guide surfaces 28^a and 28^b. These guides are adapted to engage opposite sides of a stationary guide 31, and by means of the curved surfaces 28^a and 28^b the paint stick may travel around a curve without the guides C and D binding against either side of the stationary guide 31.

As shown in Fig. 2 the guide 31 may comprise a pair of angles positioned back to back with a central guideway or channel therebetween for housing an endless chain conveyor

32, operated from a source of power. The chain at intervals along its length has upwardly projecting pusher dogs pivoted to links of the chain. The pusher dog 33 will engage the bar 9 and propel it together with the automobile body along the floor. The guides C and D will control the direction of travel of the body and the curvature of the guide faces will permit the body to swing 10 around corners during its travel.

In addition the adjustable clamping members 17 and 14 are constructed to enable the paint stick to be attached to different size bodies or to accommodate body sills of varying construction. The strip 10 is provided with slots or openings 7 through which the lower ends of bolts 20 project, these openings permitting the nuts 21 to be screwed onto the bolts from underneath the paint stick.

20 What I claim is:

1. A device for carrying automobile bodies previous to the assembly of the body on its chassis, comprising a relatively narrow channel formed bar, means for retaining the body in position on said bar against substantial displacement, and a caster mounted beneath said bar adjacent each end thereof.

2. A paint stick for automobile bodies comprising a pair of spaced casters, a member connecting said casters, and means for detachably connecting said member to the sills of the body to support the bottom of the body approximately at the height of said casters.

3. A device for carrying automobile bodies previous to the assembly of the body on its chassis, comprising a relatively narrow channel formed member having depending flanges, casters mounted at opposite ends thereof, and a guide mounted between said flanges and supported thereby.

4. A device of the class described for carrying an automobile body, comprising a structural member angular in cross section adapted to extend beneath the body to permit the bottom of the body to be mounted thereon, said member being positioned to provide depending flanges, and caster structures having a portion thereof mounted between said flanges.

5. A paint stick for automobile bodies comprising a channel bar adapted to extend transversely beneath the body in supporting engagement therewith, means for releasably connecting the bar to the body, and casters carried by said bar.

6. A paint stick for automobile bodies comprising an inverted channel bar adapted to extend transversely beneath the body in supporting engagement therewith, means for releasably connecting said bar to the body, and casters mounted within the channel of the bar.

7. A paint stick for automobile bodies comprising a bar adapted to extend trans-

versely beneath the body in supporting engagement therewith, means for releasably connecting the bar to the body, casters carried by said bar, and guide means carried by the bar and adapted to cooperate with a stationary guide during the travel of the body on the paint stick.

8. A paint stick for automobile bodies comprising a bar having supporting casters, clamping devices carried by the bar for releasably securing it to the opposite bottom sills of the body, each device comprising a fixed abutment and a movable member adapted to clamp the sill against said abutment.

9. A supporting device for carrying an automobile body previous to the assembly of the body on its chassis, comprising a member adapted to span the bottom of the body and permitting the body to rest thereon, swivelled casters mounted adjacent opposite ends of said member, and means for releasably securing the bottom of the body to said member.

10. A paint stick for automobile bodies comprising a channel bar having casters, and adjustable means carried by said bar for releasably securing the same to bodies of varying construction or size and including an adjusting bolt and a slot in said bar for receiving said bolt.

11. A paint stick for automobile bodies comprising a supporting bar having casters, and adjustable means carried by said bar for releasably securing the same to bodies of varying construction or size, and including a fixed abutment and a clamp slidable toward or from said abutment.

12. A paint stick for automobile bodies comprising a supporting bar having casters, and adjustable means carried by said bar for releasably securing the same to bodies of varying construction or size, and guide means carried by the paint stick and adapted to cooperate with a stationary structure during the travel of the body upon the paint stick.

13. A paint stick for automobile bodies or the like comprising a bar adapted to extend beneath the body in engagement therewith, casters swivelled to said bar, and a guide projecting from said bar between said casters for guiding the body during its travel on the paint stick.

14. A paint stick for automobile bodies or the like comprising a bar for supporting the body, antifriction rolls carried by said bar, and a pair of depending spaced guides secured to the bar, said guides having oppositely curved guiding faces.

15. A paint stick comprising a channel bar having a top horizontal flange for supporting the body and spaced depending side flanges, casters secured to said channel bar between the depending flanges thereof,

and means for detachably connecting the paint stick to the body.

5 16. A device of the class described for carrying an automobile body previous to the assembly of the body on its chassis, comprising a relatively narrow structural member, means for retaining the body in position on

said member, a pair of casters and means for mounting the casters adjacent opposite ends of the member to support the member substantially at the height of the casters. 10

Is testimony whereof I affix my signature.

ROBERT T. ROMINE.
